UNITED STATES PATENT OFFICE.

EDMUND J. FEENY, OF OTTAWA, ILLINOIS, ASSIGNOR OF ELEVEN-TWENTIETHS TO MAURICE T. MOLONEY, OF SAME PLACE.

PUMP-CYLINDER.

SPECIFICATION forming part of Letters Patent No. 624,917, dated May 16, 1899.

Application filed April 8, 1898. Serial No. 676,965. (No model.)

To all whom it may concern:

Be it known that I, EDMUND J. FEENY, a citizen of the United States, residing at Ottawa, in the county of La Salle and State of Illinois, have invented a certain new and useful Improvement in Pump-Cylinders, of which the following is a full, clear, concise, and exact description, reference being had to the accompanying drawings, forming a part of this specification.

My invention relates to a pump-cylinder, more particularly to a construction adapted for deep wells, which must necessarily be made of small bore and diameter; and my object is primarily to produce a form of pump-cylinder wherein the capacity may be practically doubled without necessarily increasing the diameter of the pump-cylinder, and consequently the bore of the well, and whereby a continuous flow will result—that is, a flow both upon the up and down strokes of the pump-rod.

In pump-cylinders as usually constructed the water is ejected or raised only on the up-stroke, or where double-acting and water is ejected on the up and down strokes half of the usual amount for single-acting pumps is ejected on the up and the other half on the down stroke, so that a continuous flow results without increase in capacity. By the present invention the flow may be made continuous and at the same time practically doubled.

In accordance with my invention the pump-cylinder is provided with the usual inlet-valve at the lower end, and the reciprocating piston on the pump-rod carries the usual outlet-valve. The piston acts in the usual manner to raise a column of water on the upstroke, but carries means for displacing a body of water in the pump-cylinder on the down-stroke to thus force the displaced body of water through the outlet-valve of the piston on the downstroke and up the tube or casing to the spout or outlet. This displacing device comprises an auxiliary cylinder and piston placed within the main cylinder and operated by the descent of the main piston to displace a body of water. I mount the auxiliary cylinder on the lower side of the main piston to

move therewith, while the auxiliary piston remains stationary. The pump-cylinder may be made of increased length to afford the increased capacity; but the auxiliary parts may be added without increasing the diameter of the pump-cylinder.

I have illustrated my invention in the accompanying drawings, in which—

Figure 1 is a sectional view of the pump-cylinder of my invention. Fig. 2 is a view of the piston and plunger removed. Fig. 3 is a sectional view on line 3 3, Fig. 1. Fig. 4 is a sectional view on line 4 4, Fig. 1.

Like letters refer to like parts in the several figures.

The pump-cylinder *a* is provided at the lower end with a cap *a'*, upon which is mounted the inlet-valve *a²*. The upper end of the pump-cylinder carries a cap *a³*, connected with the tube or casing *a⁴*. Within the cylinder moves a piston *b*, mounted upon the pump-rod *b'* and carrying the usual outlet-valve *b²*. To the lower side of the piston *b* is secured the auxiliary cylinder *c*, adapted to be moved up and down with the piston, and within the auxiliary cylinder *c* is provided the auxiliary piston *c'*, which is mounted upon the lower end of a pipe or tube *c²*, communicating with and supported upon a transverse pipe or tube *c³*, communicating with the atmosphere. The piston *c'* is thus held in a stationary position, and the lower face of the piston *c'* is in communication with the atmosphere to avoid the formation of a vacuum or the compression of the air within the auxiliary cylinder during the operation of the pump. The auxiliary cylinder *c* is illustrated as connected with the lower face of the piston *b*, through the agency of an extended tubular portion provided with slots *c⁴* to accommodate the stationary cross-piece *c⁵*. It is not necessary, however, to make this connecting portion tubular, and any other desired means may be employed for connecting the auxiliary cylinder *c* with the piston *b*.

During the operation of the pump the ascent of the piston serves in the usual manner to open the inlet-valve *a²* and draw the fluid into the pump-cylinder through the action of suction. Upon the descent of the piston and

auxiliary cylinder *c* the auxiliary cylinder displaces a body of water in the pump-cylinder equal to its own volume, and this body of water during the downstroke of the piston is forced upward through the outlet-valve *b*² and thence up the tube of the well and out through the spout of the pump. During the downstroke the piston *b* is in the usual manner moved to a position beneath a column of water in the upper end of the pump-cylinder, and in the upward stroke this column of water is lifted and ejected. Thus during both of the strokes water is ejected, and by making the auxiliary cylinder as large as is consistent with the flow of water upward between the auxiliary cylinder and the pump-cylinder the capacity of the pump may be practically doubled, since upon the upstroke as well as upon the downstroke a body of water is ejected which is equal to the body of water ejected by an ordinary single-acting pump during a complete up-and-down stroke.

Having fully described my invention, what I claim as new, and desire to secure by Letters 25 Patent, is—

1. In combination, a pump-cylinder having a valve at the lower end, a plunger moving therein, an auxiliary cylinder secured to and moving with said plunger and of a size to

leave a fluid-passage between the main and auxiliary cylinders, and a piston within said auxiliary cylinder fixed in position, substantially as described. 30

2. In combination, a pump-cylinder having a valve at the lower end, a plunger moving 35 therein, an auxiliary cylinder closed at one end and a piston therein, both arranged in the space between the plunger and the valve at the lower end of the pump-cylinder and associated with the plunger to cause the piston and the closed end of the auxiliary cylinder to approach during the ascent of the plunger and to recede during the descent of the plunger to vary the effective volume of the pump-cylinder, substantially as described. 40

3. In combination, the pump-cylinder and the plunger therein, the auxiliary cylinder *c*, the piston *c'*, and the supporting-pipes *c*² *c*³ affording an air-passage to the interior of the auxiliary cylinder, substantially as described. 45

In witness whereof I have hereunto subscribed my name in the presence of two witnesses.

EDMUND J. FEENY.
